UNITED STATES PATENT OFFICE.

THOMAS WILSON PATERSON, OF VICTORIA, CANADA.

TRACK-LAYING MACHINE.

SPECIFICATION forming part of Letters Patent No. 529,830, dated November 27, 1894.

Application filed July 2, 1894. Serial No. 516,281. (No model.) Patented in Canada July 16, 1894, No. 46,593.

To all whom it may concern:

Be it known that I, THOMAS WILSON PATERSON, a subject of the Queen of England, residing at Victoria, Province of British Columbia, Dominion of Canada, have invented a new and useful Track-Laying Machine, (for which I have obtained a patent, No. 46,593, dated July 16, 1894, in the Dominion of Canada,) of which the following is a specification.

10 My invention relates to improvements in track laying machines, in which sprocket wheels, and "Ewart" chains, are operated from the axle of an ordinary car, for laying railway ties, in conjunction with a center car, running on rails placed on top of flat cars, for bringing forward the ties from the rear cars, and depositing them on the two side cars; secondly, in depositing the rails, on each side on top of ties, ready for spiking, by means of a

20 traveler, running on a curved overhead track.

I attain these objects by the mechanism illustrated in the accompanying drawings, in which—

Figure 1, is a side elevation of the machine. Fig. 2, is a plan of the machine. Fig. 3, is a side view of one of the side cars. Fig. 4, is an end view of one of the side cars. Fig. 5, is a side view of the center car. Fig. 6, is a plan of the center car. Fig. 7, is an end view of the traveler and overhead track. Fig. 8, is a side view of the traveler and overhead track. Fig. 9, is the tongs for grasping the rails. Fig. 10, is the rollers and brackets to go in stake pockets.

35 Similar letters refer to similar parts throughout the several views.

a is an ordinary flat car, on the axle of which a sprocket wheel b, in halves, is clamped.

C is a "Ewart" chain, running sprocket wheel d; and through shaft e, giving motion to two sprocket wheels f, f, by means of which the "Ewart" chains g, g, running on wood beds h, h; and returning under sheaves i, i; carry the ties along, and drops them over on

40 to the bed of the track, as the car moves ahead on the rails already laid down; the speed of the carrying chains g, g, being so proportioned as to move at the same rate as the car.

j is the center car, for bringing the ties from the cars in rear, on which the ties are raised 50 up a sufficient height for the car j, to run under, when the wrought iron frame k, is let down.

l is a shaft with a ratchet wheel m; chain n; bell crank o; connecting rods p, p; for lifting or lowering the frame k; which is carried on side links q, q, &c., pivoted to sides of car. The car is run under the ties with the frame k, let down. The frame is then lifted, by the mechanism described, and takes a load of ties. 60

R, R, are side cars, made the proper height to run under the ends of the ties on car j. The frame k, is then let down, and the ties are deposited on the side cars R, R, ready for distributing on the carrying chains g, g. 65

s, s, s, s, are rails laid on top of flat cars, for the tie cars to run on.

t, t, &c., are brackets to hang on the stake pockets. The rails to be laid are brought along from the rear cars on the rollers u, u, to front, 70 and are then grasped by the tongs v; and carried by the traveler w, on an overhead track x, made circular at end, so as to swing around the rails, and deposit them on each side on top of ties, ready for spiking. 75

y, y, are hangers for carrying the angle iron track x.

I make no claim to the rollers u, or tongs v, for I am aware that these are not new; but What I claim, as my invention, and desire 80 to secure by Letters Patent, is—

1. The combination in a track laying machine of the sprocket wheel b; "Ewart" chain C; wheels d, f, f; chains g, g; beds h, h; cars j, R, R; for laying the ties all substantially 85 as set forth.

2. The combination with the rollers u, u; tongs v; brackets t; of the traveler w; track x; for laying the rails, substantially as described.

THOMAS WILSON PATERSON.

Witnesses:

A. K. MUNRO,
WM. HOUSTON.
